Int. Cl. D25—01

U.S. Cl. D18—2

*Fig. 4.**Fig. 5.**Fig. 6.*FIG. 1 is a perspective view of either the top or the bottom of a block module for building statues, art pieces or the like showing my new design;

FIG. 2 is an elevational view of the lefthand end of the block module for building statues, art pieces or the like of FIG. 1 (the righthand end elevational view being the mirror image of FIG. 2);

FIG. 3 is a top plan view of the block module for building statues, art pieces or the like of FIG. 1 (the bottom plan view being the mirror image of FIG. 3);

FIG. 4 is a longitudinal sectional view through the lefthand portion of the block module for building statues, art pieces or the like of FIG. 1 taken along section line 4-4 (the longitudinal sectional view of the righthand portion of the block module for building statues, art pieces or the like of FIG. 1 being the inverse of that shown in this figure).

FIG. 5 is a transverse sectional view through the block module for building statues, art pieces or the like of FIG. 1 taken along section line 5-5; and

FIG. 6 is a side elevational view of the righthand end of the block module for building statues, art pieces or the like of FIG. 1 (the lefthand elevational view being the inverse of that shown in FIG. 6).

I claim:

The ornamental design for a block module for building statues, art pieces or the like, substantially as shown.
